Patented Jan. 20, 1920.

Leonard Kebler ^{INVENTOR}

EDWARDS, SAGE & RICHMOND BY ATTORNEYS

UNITED STATES PATENT OFFICE.

LEONARD KEBLER, OF BRONXVILLE, NEW YORK, ASSIGNEE TO WARD LEONARD
ELECTRIC CO., A CORPORATION OF NEW YORK.

CONTROLLING MEANS FOR ELECTRIC MOTORS.

1,328,631.

Specification of Letters Patent. Patented Jan. 20, 1920.

Application filed February 3, 1917. Serial No. 146,502.

To all whom it may concern:

Be it known that I, LEONARD KEBLER, a citizen of the United States, residing at Bronxville, in the county of Westchester 5 and State of New York, have invented certain new and useful Improvements in Controlling Means for Electric Motors, of which the following is a specification.

The principal object of my invention is to 10 provide a new and improved starting panel for electric motors. Another object of my invention is to provide a circuit breaker and a starting rheostat combined in such a way that the movable member of the rheostat 15 must be at a proper position before a normal enduring closure of the circuit breaker can be effected. Another object of my invention is to provide a circuit breaker with means for holding it in closed position in combination 20 with a starting rheostat and mechanism that will prevent the holding means from being effective at starting, unless the rheostat is properly adjusted. Another object of my invention is to provide a circuit breaker 25 to be operated by either overload or no voltage in combination with a starting rheostat and mechanism that will require a particular adjustment of this rheostat to insure proper closing of the circuit breaker at starting. Another object of my invention is to 30 provide a rheostat grid with a new and improved protective coating. All these objects and others will be made apparent in the following specification and claims taken 35 with the accompanying drawing.

In this drawing I have shown in a diagrammatic way one specific embodiment of my invention.

The two line conductors 9 and 9' to the 40 motor comprise the contacts 10 and 10' adapted to be closed respectively by the bridging pieces 12 and 12' of the circuit breaker. Each such bridging piece as 12 is carried by a pivoted arm 11 provided with 45 a handle 14 and adapted to be retracted by a spring 15 unless held in the closed position by the latch 13. Normally the latch 13 is held in effective latching position by the spring 16.

Continuing with the line conductor 9 there 50 is an overload coil 17 with an associated core 18 which carries the cross arm 19 adapted when raised to trip the latches 13 and 13'.

The motor field winding 20 is in shunt 55 connected directly across the line wires 9

and 9'. The armature starting resistance is in a series of sections 21 connected to contacts 37 as shown at the lower part of the diagram. A slide 22 is provided with a handle 23 and is mounted on appropriate 60 guides so that it can be moved up and down manually and thus connect across between any pair of contacts 37 and include more or less of the resistance 21 in series in the circuit. Thus the variable resistance 21 and 65 the armature 25 are connected in series by the conductor 24 across the line 9—9' and in shunt with the field 20.

Another conductor 28 is connected across the line wires 9—9' and comprises the no 70 voltage coil 26 and the series resistance 27. Also in the conductor 28 there is a normally closed push button switch indicated at 29. The pivoted arm 30 carries a keeper 34 adapted to be held by the no voltage coil 26 75 when the latter is sufficiently energized. The spring 31 acts in opposition to the restraint of the coil 26 on the keeper 34. An arm 33 is connected by the link 32 to the arm 30, and is pivoted so that its free end 80 lies in the path of the slide 22, when the latter is at the resistance-all-in position.

When the arm 30 is released by the under-load coil 26 and raised by the spring 31, it strikes the plunger 35 which pushes against 85 the stem 36 hanging down from the core 18 and thus raises the cross arm 19 to trip the latches 13 and 13'.

The resistance 21 is made up of a plurality of iron grids which are supported behind the panel on which the apparatus indicated in the drawing is mounted. These iron grids are coated with enamel or with comparatively infusible material. The coating 90 may be an infusible material of good 95 heat conductively or may be of the general type described in the Leonard Patents 863,293 of August 13, 1907, and 576,202 of February 2, 1897, but I mention these patents merely by way of example. This coating is infusible at the ordinary temperatures of the muffle furnace, but at the fusing temperature of iron it may become more or less viscous, still retaining a certain amount of 100 mechanical strength. Accordingly, if a 105 temperature at which the resistance grid will burn out is attained, the coat will either be quite infusible or may become plastic and tend to cement the particles of iron together. In either case it will prevent 110

ing independently closable arms, locking mechanism therefor, movable means for unlocking said mechanism, a rheostat, and means controlled by the movable element of 5 said rheostat for engaging said movable means and shifting it to an ineffective position.

17. In combination, a circuit breaker having independently closable arms, mechanism 10 for restraining said breaker in closed position, movable means for causing said restraining mechanism to be ineffective, a rheostat, and means controlled by said rheostat for engaging said movable means and shifting it to an ineffective position.

18. In combination, a circuit breaker,

mechanism for restraining said breaker in closed position, movable means for causing said restraining mechanism to be ineffective, a rheostat, a no voltage winding, and means 20 controlled by said rheostat and said no voltage winding for controlling said movable means.

19. In combination, a circuit breaker, a rheostat, correlated means to open the circuit breaker, means to hold said circuit breaker closed, and mechanism operatively associated with the rheostat to render said holding means ineffective unless the rheostat is in the initial position of adjustment. 25 30

LEONARD KEBLER.
